UNITED STATES PATENT OFFICE.

DAVID A. LEGG AND CHARLES BOGIN, OF TERRE HAUTE, INDIANA, ASSIGNORS TO COMMERCIAL SOLVENTS CORPORATION, OF TERRE HAUTE, INDIANA, A CORPORATION OF MARYLAND.

PRODUCTION OF ESTERS.

Application filed June 16, 1923. Serial No. 645,756.

To all whom it may concern:

Be it known that we, DAVID A. LEGG, a subject of the King of Great Britain and Ireland, and CHARLES BOGIN, a citizen of the 5 United States, both residents of Terre Haute, in the county of Vigo and State of Indiana, have invented certain new and useful Improvements in the Production of Esters, of which the following is a specification, reference being made to the accompanying drawings, forming a part thereof.

Our invention relates particularly to the production of esters during the catalytic dehydrogenation of aliphatic aldehyde-forming alcohols in the vapor phase, and the objects of our invention are, among other things to provide a novel simplified method by which such esters may be readily formed from the corresponding alcohol by the reaction occurring in the vapor phase in the presence of particular forms of catalysts.

It is well known that the catalytic interaction of aldehydes to form esters has been applied on a laboratory scale in the liquid 25 phase, as set forth by Tischchenko, Beilstein, "Handbuch der Organischen Chemie," 4th Edition, vol. 2, page 291. This general equation may be expressed as follows:—

30 wherein R represents a hydrocarbon radicle.

We have discovered a new and useful method of utilizing this reaction occurring in the vapor phase in the presence of certain 35 hereinafter described catalysts resulting in far better yields than have hitherto been obtained in industrial scale operations.

While our invention is capable of embodiment in many different forms, for the purpose of illustration we shall describe only 40 one form of our method; and while said method is capable of being carried out with many different types of apparatus, yet for the purpose of illustration we have shown 45 only a diagrammatic representation, partly in section, of the apparatus shown and described in the Legg & Hancock application for patent filed in the U. S. Patent Office February 20, 1923, Serial No. 620,165, which 50 apparatus has been successfully used for the dehydrogenation of normal butyl alcohol in the production of normal butyl aldehyde and normal butyl butyrate.

In the drawing we have shown only a sin-

gle unit of the apparatus; however two or 55 more units connected in series may be used to better advantage.

Referring to the drawing in order to understand how our improved method may be carried out, a quantity of alcohol, for example, normal butyl alcohol is poured in the reservoir 1 set on the shelf 2 from which it flows by gravity through the pipe 3 at a definite rate through sight feed-gauge glasses 4 and then by pipe 5 into the steam preheater 6 heated by live steam from the inlet pipe 7. Within the preheater 6 is the flash boiler 8 preferably formed in a copper coil with the copper coil pipe 9 leading from the boiler 8 to the conduit 10. The condensed steam from the pre-heater 6 is discharged through the outlet pipe 11. During the course of this run the butyl alcohol is vaporized and then preheated to 125° C. or even higher after which it is passed through 75 conduit 10 into the catalyzer.

The catalyzing apparatus comprises the outer heat baffle cylinder 12 suitably set in brickwork 13 having lateral spaced-apart baffles 14. Set within the cylinder 12 is the container 15 supported on the annular bracket 16 by the circular bead 17 extending from the open rim of the container 15. Projecting from the sides of the container 15 are lateral spaced-apart baffles 18 dovetailed 85 between the baffles 14. The bottom of the container 15 has a series of downwardly-extending ribs 19 over the gas-jets 20 formed in the top of the burner 21 connected by the pipe 22 with any suitable source of gas supply (not shown).

Supported concentrically within the container 15 is the outer catalyst cylinder 23 having the inlet core 24 connected at its upper end to the conduit 10; the core 24 opens 95 at its lower end into the vapor distributing chamber 25 formed in the bottom of the cylinder 23. Concentrically disposed within the cylinder 23 is the inner catalyst area 27 filled preferably with a suitably prepared catalyst such as is described in United States Legg Patent No. 1,401,117 dated December 20, 1921. The lower end of the cylinder 26 rests on the plate 28 the marginal periphery 100 of which is perforated to allow the vapors to pass from the chamber 25 into the catalyst area 27. The upper portion of the cylinder 26 is formed with the chamber 29 hav-

ing holes in its sidewalls through which the reaction products pass (as indicated by arrows) through the outlet pipe 30 to the condenser 31 having the usual inlet and outlet pipes 32 and 33 respectively for cooling water which circulates about the coil 34 within the condenser 31. The condensed products pass from the coil 34 through the pipe 35 and are caught in any suitable receiver 36 set on standards 37. The container 15 holds any suitable heat exchanging medium 38, in the present instance, a bath of molten solder is preferably used.

As an example of the use of our improved method in carrying out same in industrial practice, 6600 pounds of normal butyl alcohol were placed in reservoir 1 and then vaporized and heated to about 125° C. in the preheater 6 from which the vapors passed through the inlet conduit 10 and inner core 24 to the vapor distributing chamber 25 and thence upwardly as indicated by the arrows through the perforations in the plate 28 into the catalyst area 27 which was filled with a fused cupric oxide catalyst formed as a fused, spongy mass, and crushed into lumps of suitable size, say of one inch cubes, such as is described in the aforesaid United States Legg Patent No. 1,401,117. Here the alcohol vapors were decomposed with a resultant mixture consisting largely of butyric aldehyde, butyl alcohol, butyl butyrate and hydrogen. Such reaction products were then passed through the outlet pipe 30 to another similar unit and then to the condenser 31 in the usual manner to separate the hydrogen. During this decomposing operation the molten solder 38 in the container 15 surrounding the catalyst and vapors was maintained at a temperature ranging from 280° C. to 300° C. by means of the gas jets 20.

The crude condensed product caught in the receiver 36 consisting of butyric aldehyde, butyl alcohol, butyl butyrate and butylidene dibutyl ether was then distilled to separate the aldehyde therefrom and the residue was then distilled with dilute sulphuric acid (1 to 2%) to decompose the butylidene dibutyl ether.

We found the distillate from this mixture consisted of three main fractions, viz:—

- A. Butyraldehyde.
- B. Butyl aldehyde and butyl alcohol and water.
- C. Butyl alcohol and butyl butyrate and water.

The "C" fraction was then run into a separating tank and the lower layer of water removed; the residue was then distilled to remove as much butyl alcohol as possible, and the final residue consisting of 1050 pounds was found to contain 52% butyl butyrate. This butyl butyrate can be readily separated from butyl alcohol by distillation

because of the wide difference between the boiling points of butyl alcohol (117° C.) and of butyl butyrate (165° C.). Any recovered butyl alcohol can again be utilized in our process by introducing same into the reservoir 1.

It will be understood that many modifications may be made in the form and arrangement of the apparatus used for carrying out our improved method for the production of esters without changing the essential principles of the process or the operation in such apparatus.

We claim as our invention:

1. The method of producing esters which comprises passing normal butyl alcohol in the vapor phase over a dehydrogenating copper-containing catalyst at a temperature between 260 and 320° C., then separating part of the aldehyde produced, and finally fractionating the residue to recover the esters formed therein.

2. The method of producing esters which comprises preheating vaporized normal butyl alcohol to a temperature of about 125° C., then passing same over a dehydrogenating copper-containing catalyst at a temperature between 260 and 320° C., then separating part of the aldehyde produced, and finally fractionating the residue to recover the esters formed therein.

3. The method for producing butyl butyrate which comprises passing normal butyl alcohol in the vapor phase over a copper catalyst at a temperature between 260 and 320° C., then condensing the reaction mixture to remove hydrogen, then distilling the resultant product to separate part of the aldehyde produced, and finally separating from the distillate the water and butyl alcohol with the recovery of butyl butyrate therefrom.

4. The method for producing butyl butyrate which comprises preheating vaporized normal butyl alcohol to a temperature of about 125° C., then passing it over a dehydrogenating catalyst comprising fused and crushed cupric oxide at a temperature between 260 and 320° C., then condensing the reaction mixture to remove hydrogen, then distilling the resultant product to separate part of the aldehyde produced, and finally separating the butyl butyrate formed from the butyl alcohol and water.

5. In the method for producing esters from normal butyl alcohol the steps which consist in subjecting the alcohol in a vapor phase to the action of a dehydrogenating copper-containing catalyst at a temperature between 260 and 320° C. and thereafter condensing, distilling the resultant product to separate part of the aldehyde produced, and finally separating and recovering esters formed in the residue.

6. In the method for producing esters

from normal butyl alcohol the steps which consist in subjecting the alcohol in a vapor phase to the action of a dehydrogenating ester-producing catalyst comprising fused and crushed cupric oxide at a temperature between 260 and 320° C. and thereafter condensing, distilling the resultant product to separate part of the aldehyde produced, and finally separating and recovering esters formed in the residue.

7. In the method for producing butyl butyrate from normal butyl alcohol the

steps which consist in subjecting the vaporized alcohol preheated to a temperature of about 125° C. to the action of a dehydrogenating catalyst comprising fused and crushed cupric oxide at a temperature between 26° and 320° C. and thereafter condensing, distilling the resultant product to separate part of the aldehyde produced, and finally separating and recovering esters formed in the residue.

DAVID A. LEGG.
CHAS. BOGIN.
